UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF VIRGINIA.

TABLE-BED.

1,246,611.

Specification of Letters Patent. Patented Nov. 13, 1917.

Application filed September 20, 1913, Serial No. 790,855. Renewed September 17, 1917. Serial No. 191,895.

To all whom it may concern:

Be it known that I, CARL R. KLOK, a citizen of the United States of America, and resident of Chicago, Cook county, Illinois, 5 have invented a certain new and useful Improvement in Table-Beds, of which the following is a specification.

My invention relates to folding beds of that kind in which the bed when folded is 10 concealed within the body of a table or other article of furniture.

Generally stated, the object of my invention is to provide a novel and highly efficient folding bed of the foregoing general character.

A special object is to provide a construction in which the bed is entirely outside of the table when in use, and in which the bed frame, when folded into a flat bundle, must 20 turn up side down in order to assume a position within the table, the axis of rotation being at one side of the table, whereby the table top may be used while the bed is unfolded.

It is also an object to provide certain details and features of construction tending to increase the general efficiency of a table bed of this particular character.

In the accompanying drawings:—

Figure 1 is a longitudinal section on line 30 1—1 in Fig. 2.

Fig. 2 is a cross section on line 2—2 in Fig. 1.

Fig. 3 is a view similar to Fig. 2, but 35 showing the bed swung out of the table and thus brought into position for unfolding.

Fig. 4 shows the bed unfolded and in condition for use.

As thus illustrated, my invention comprises a table body A having fixed ends a, a fixed side a¹, and fixed legs a². The top a³ is hinged at a⁴, and the side wall a⁵ is hinged at a⁶. By raising the top the side wall a⁵ can swing down and into the position shown 45 in Figs. 3 and 4.

The bed comprises a rectangular frame B of angle iron, and is composed of sections b, b¹ and b². The sections b and b¹ are connected by relatively long links b³, and the 50 sections b¹ and b² are connected by relatively short links b⁴. The section b is pivoted at b⁵ to the table body, and is provided with folding legs b⁶, the upper ends of which latter are connected by links b⁷ with the sides of the

section. These links have slots b⁸ which engage the headed pins b⁹ on the bed frame, whereby said legs can fold. Similar legs b¹⁰ and b¹¹ are pivoted to the sections b¹ and b², and are connected by links b¹² and b¹³ with the links b³ and b⁴, whereby said legs 60 fold and unfold automatically. The said links b³ and b⁴ have end portions which overhang the sections, and which prevent the frame from unfolding farther than the horizontal. When the frame is folded, these 65 links b³ and b⁴ provide space for the mattress and bedding, whereby the entire bed can be folded within the table.

When folded into the position shown in Fig. 3, the flat bundle thus formed by the 70 frame B must be rotated about the pivots b⁵, in order to swing the bed into the table. In this position the bed rests on stops C, and the bed is held against unfolding by any suitable means, as by a strap (not 75 shown) buttoned around the same. It will be seen that when thus concealed within the table the bundle can bulge downward, but cannot bulge upward, whereby the top a³ is always closed without difficulty. In this 80 way, and by turning the bed upside down, no trouble can be experienced in closing the top of the table, even though the mattress and bedding may be thicker than usual. Also, moreover, the table top can be used 85 while the bed is in use, which is very often a convenience.

The axes of folding motion produced by the pivots of the links b³ and b⁴ are all parallel and extend transversely of the bed, 90 regardless of the width thereof, inasmuch as the sections b and b² are head and foot sections of the frame, the axis produced by the pivots b⁵ is fixed and extends along on one side of the table, being parallel with the 95 axes of said frame.

The table is of the right height for use as a library or desk table, having the proper clearance underneath. Also, the bed is of standard height. Thus the two things are 100 combined without interfering with each other. In other words, neither one is sacrificed for the other.

Obviously, therefore, the invention affords one method of solving some of the problems 105 involved in the construction of a practical article of furniture of this kind, in which a folding bed frame of this particular char-

acter is combined with a table, but it will be understood is not limited to the exact construction shown and described.

What I claim as my invention is:—

5 1. A table bed comprising a table body, a bed frame foldable into a bundle outside of said body, and means for pivotally mounting the frame in the body, requiring the bundle to swing upside down about a horizontal axis at one side of the body, after the frame is entirely folded, to bring the same within said body.

10 2. A table bed comprising a table body, a bed frame foldable transversely thereof into a bundle outside of said body, and means for pivotally mounting the frame in the body, requiring the bundle to swing upside down about a horizontal axis at one side of the body, after the frame is entirely folded, to bring the same within said body, and a top for said body, adapted to remain in position while the bed is in use.

15 3. A table bed comprising a table body, a bed frame foldable into a bundle outside of said body, and means for pivotally mounting the frame in the body, requiring the bundle to swing upward and over and upside down, after the frame is entirely folded, to bring the same within said body, said 20 frame comprising three long and two short pivotally connected sections, and said means being applied to one end of the frame, the said bed thereby having a plurality of parallel axes of folding motion, one of which is 25 formed by said means.

30 4. A table bed comprising a table body, a bed frame foldable transversely thereof into a bundle outside of said body, and means for pivotally mounting the frame in the body, requiring the bundle to swing upside down, after the frame is entirely folded, to bring the same within said body, and legs 35 for the sides of said frame, extending hori-

zontally when the bed is folded within the table, said frame having means for automatically folding and unfolding said legs by the folding and unfolding of the bed. 45

5 5. A table bed provided with a transversely folding bed adapted to be concealed therein, provided with means whereby the bed swings bodily out of the table before being unfolded for use, said swinging motion being about a horizontal axis extending transversely of one end of said bed and said axis of swinging movement being fixed relative to one section of the folding bed-frame. 50

6. A table bed provided with a transversely folding bed adapted to be concealed therein, provided with means whereby the bed swings bodily out of the table before being unfolded for use, said swinging motion being about a horizontal axis extending transversely of one end of said bed, said bed comprising a plurality of pivotally connected sections, and folding legs for each section, the axis of said sections being parallel with said axis of bodily movement, and said axis of swinging movement being fixed relative to one section of the folding bed-frame. 65

7. A table bed provided with a transversely folding bed adapted to be concealed therein, provided with means whereby the bed swings bodily out of the table before being unfolded for use, and a table top movable to permit movement of the bed in and out of the table, adapted to remain in position while the bed is in use and said axis of swinging movement being fixed relative to one section of the folding bed-frame. 70

Signed by me at Chicago, Illinois, this 80
11th day of September, 1913.

CARL R. KLOK.
